UNITED STATES PATENT OFFICE.

JOHN SIMPSON, OF CLEVELAND, OHIO.

IMPROVEMENT IN MOP-HEADS.

Specification forming part of Letters Patent No. 150,797, dated May 12, 1874; application filed February 23, 1874.

To all whom it may concern:

Be it known that I, JOHN SIMPSON, of Cleveland, in the county of Cuyahoga and State of Ohio, have invented a certain new and Improved Mop-Head; and I do hereby declare that the following is a full, clear, and complete description thereof, reference being had to the accompanying drawings, making a part of the same.

Figure 1 is a side view of the mop-head. Fig. 2 is a vertical section. Fig. 3 is a top view. Fig. 4 is an edge view.

Like letters of reference refer to like parts in the several views.

The nature of this invention relates to a mop-head, the construction and operation of which are as follows:

In the drawings, A represents a round wire-frame, the two ends of which are firmly secured to the arms B of a nut, C. The nut is made of malleable iron. The arms B are cast flat and somewhat thin, so that they can be easily bent around the ends of the wire frame, forming a socket, in which they are held, as shown in Fig. 2. To the nut is fitted a hollow screw, D, provided with finger-pieces E, whereby it is worked in the nut. F is a cross-head, having a hollow stem or socket, G, fitted loosely to the inside of the screw D, and on

which it turns for moving the cross-head. The socket is prevented from pulling out from the screw by means of the nibs a projecting from the edge of the socket over onto the edge of the screw, shown as in Fig. 3.

The practical use of the mop-head is as follows: A handle, H, is inserted in the socket, and secured therein by a pin driven into it through the ear C. The bar or cross-head is raised, as indicated by the dotted line d, by turning the screw. Into the space between the cross-head and bar of the frame are drawn cloths for the mop, as shown at I. The cloths thus hanging on the bar of the frame are there retained by the cross-head, which is now screwed down upon them, as shown in Fig. 1. A deep groove in the edge of the cross-head binds them tightly to the bar, so that they cannot be pulled out.

Having thus fully described my invention, what I claim, and desire to secure by Letters Patent, is—

The combination of the cross-head F and screw D with the socket G and nut C, as and for the purpose herein specified.

JOHN SIMPSON.
